United States Patent Office

Des. 224,188
Patented July 11, 1972

224,188

CHAIR

Gardner Leaver, New York, N.Y., assignor to Steelcase
Inc., Grand Rapids, Mich.

Continuation-in-part of design application Ser. No.
16,351, Mar. 20, 1969. This application Sept. 4,
1970, Ser. No. 24,841

Term of patent 14 years

Int. Cl. D6—02

U.S. Cl. D6—20

FIG. 1.

FIG. 2.

FIG. 3.

FIG. 6.

FIG. 7.

FIG. 4.

FIG. 5.

FIG. 1 is a perspective view of the chair;
 FIG. 2 is a front perspective view of the chair;
 FIG. 3 is a side perspective view of the chair;
 FIG. 4 is a rear perspective view of the chair;
 FIG. 5 is a top perspective view of the chair;
 FIG. 6 is a perspective view of an alternative embodiment of the chair wherein a headrest has been added;

FIG. 7 is a rear perspective view of the alternative embodiment shown in FIG. 6.

This application is a continuation-in-part of the application for a design for a chair, Ser. No. D. 16,351 filed on Mar. 20, 1969, and now Pat. No. D. 218,816.

I claim:

The ornamental design for a chair, substantially as shown and described.
